SHEET METAL FLUME TROUGH

Albert Colwell Norton, Berkeley, Calif., assignor
to California Corrugated Culvert Co., Alameda
County, Calif., a corporation of California

Application June 26, 1933, Serial No. 677,650

2 Claims. (Cl. 61—14)

This is a continuation in part of my application for Method of making sheet metal flume troughs, Serial No. 608,396, filed April 30th, 1932, now United States Letters Patent No. 1,937,663, and relates to sheet metal troughs used in flumes for the transportation of water.

Sheet metal flume troughs are commonly formed initially to semicircular cross section. It is well known in the art, however, that such cross section is distorted under load, and tends to assume a curvature corresponding approximately to the hydraulic catenary. Such distortion is resisted to some extent by the stiffness of the sheet metal, and still more by the suspending rods and the transverse joints between adjacent trough sections, said joints usually including both transverse beads formed in the metal of the trough section and transverse clamping rods. The curvature of the trough also changes with variations in load, the deflection from the semicircle being greatest when the trough is about half full of water, and decreasing as the load approaches the maximum.

Distortion of initially semicircular sheet metal flumes has caused much annoyance and expense by producing leaks at the joints, especially at the ends of the flume, where the sheet-metal trough joins rigid structures such as concrete head walls, and at horizontal bends or angles in the flume, as will be explained fully hereinafter. Attempts have been made to overcome this leakage by forming the concrete structure to a theoretical catenary curvature where it is in contact with the sheet metal trough. Such attempts have not been successful, because of the fact that the curvature assumed by the loaded trough is not a true catenary, and cannot be calculated by any mathematical formula heretofore known.

I have found it possible to overcome the above described difficulties inherent in the semicircular sheet metal flume, and to prevent leakage and loosening of the joints and suspension rods, by forming the trough initially to a curve which may be defined broadly as the mean between the limits of distortion caused by variations in load, and which can be laid out about three major centers whose positions may be expressed as functions of the width across the top of the trough. I have also developed a simple and inexpensive method of forming the sheet to the compound curve above mentioned, as described and claimed in my United States Letters Patent No. 1,937,663 referred to above, all of which results in a flume superior to those now in use. The employment of a sheet metal trough of compound curvature

also enables me to make important economies in the supporting substructure, as described and claimed in my United States Letters Patent No. 1,878,289, for flumes.

My invention will now be described in detail with reference to the accompanying drawings, it being understood that changes may be made, within the limits of the claims hereto appended, without departing from the spirit of the invention as defined in said claims.

In the drawings:—

Fig. 1 is a part sectional plan of a flume embodying my improved trough, showing it connected with a concrete head wall at one end, and at another portion provided with a horizontal bend or angular deflection.

Fig. 2 is a transverse section of the same.

Fig. 3 is a diagram illustrating the layout of the compound curve upon which the trough is formed, and showing the deflection from the semicircle and the limits thereof under varying loads.

Fig. 4 is a plan view of the cut blank or sheet from which the angle section shown in Fig. 1 is formed.

Referring more particularly to the drawings, the reference numeral 1 designates a trough formed from sheet metal with a rounded bottom 2 and divergent sides 3, the latter being curved inwardly upon a radius greater than that of said bottom. The trough is suspended by rods 4 extending transversely beneath it, the ends of said rods being secured to the frame or substructure, a conventional form of which is shown in Figs. 1 and 2 as comprising longitudinal stringers 5 and cross bars 6. In my improved construction, the upper portions of the sides 3 of the trough diverge at angles of about 16 degrees from the vertical, and the upper end portions of the rods 4, where they are attached to the frame, are also positioned at the same angle.

My trough 1 is formed of any suitable metal, preferably galvanized sheet steel of the weight and stiffness ordinarily used in such structures. Its cross sectional shape is a compound curve drawn about three major centers, with narrow transition areas of changing radius connecting the major arcs. In the theoretical consideration of the curve, these transition areas may be ignored, however. The curve and its mathematical layout are illustrated diagrammatically in Fig. 3, in which the heavy solid line 1a is the curve upon which the trough 1 is formed, 2a being the central arc of shorter radius and 3a the side arcs of longer radius, corresponding respectively to 110

the bottom 2 and sides 3 of the trough. The curve 1a is constructed as follows:—

Upon a horizontal line $d-d$, whose length D is the desired width across the top of the trough,

- 5 construct a semicircle with D as its diameter, as shown by the light solid line b. The length of said semicircle, i. e. one half the circumference of a circle whose diameter is D, or $1.5708D$, will be the width of the sheet from which the trough
- 10 is to be formed. Draw a vertical line c-c through the center C of the semicircle. Locate the points O on either side of the vertical center line c-c and above the horizontal line $d-d$, the horizontal distance A between said points O and the
- 15 vertical center line being approximately equal to $0.317D$, and their vertical distance B above the horizontal line being approximately equal to $0.173D$. Using the points O as centers, and the greater distance Od, or R, as radius, draw arcs 20 3a downwardly from the line $d-d$. The distance Od, or R, is approximately equal to $0.834D$, and is the radius of curvature of the divergent sides 3 of the trough. Now locate O' upon the vertical center line at a distance Q, approximately equal to 25 $0.147D$ below the horizontal line. Then with O' as a center and with radius S approximately equal to $0.384D$, draw the arc 2a intersecting and joining the arcs 3a. The arc 2a corresponds to the bottom 2 of the trough. The result is the 30 compound curve shown by the solid line 1a. It is not a true catenary, but is an experimental curve drawn about three fixed centers.

The curve above described was originally determined empirically. A semicircular sheet metal

- 35 trough of standard weight was loaded until it showed, by actual measurement, its maximum deflection. This maximum deflection, indicated in Fig. 3 by the broken line e, occurred when the trough was between one-third and one-half full of water. As the load was increased, the deflection decreased, until, when the trough was loaded to maximum capacity, the measured deflection was as shown by the broken line f. Upon reducing the load, the measured deflection first increased to the broken line e, and then subsequently decreased, but never decreased beyond the broken line f even when the trough was empty, the metal having received a permanent set which prevented it from returning closer to 45 semicircular form than the maximum load curve f. The curves e and f therefore represent the limits of deflection or distortion to which the trough is subjected under all conditions of varying load. When these limits were determined 50 and plotted as the curves e and f, a curve representing a mean was drawn between them, and this mean (the curve 1a) was found to be formed almost exactly about the three centers O and O', whose positions, as well as the radii R and S of 55 the compound curve, could be expressed in terms of the diameter D.

It will be apparent that, by initially forming my trough to the compound curve described above, I have not only eliminated entirely the major distortion from semicircular form which occurs upon the initial loading of the flume, but I have also reduced by fifty per cent the effects of the subsequent distortion due to variations in load. My flume, having an initial and natural (i. e. 65 when not under stress) curvature corresponding to the mean of the maximum and minimum load distortion, is only deflected by an amount equal to one-half the maximum in either direction, which is a negligible factor in causing leaks and 70 deterioration. Moreover, there is no appreciable

variation with changes in load in the inclination of the upper portions of the trough sides 3 and suspension rods 4, so that bending of said rods, at their points of attachment to the frame, is reduced to a negligible quantity.

The numerical values stated herein for the radii R and S and the co-ordinates of the centers O and O' are those which give best results under average conditions. Obviously, however, it may be desirable to vary said values slightly to suit particular conditions in some cases, and such variations are to be considered as included within the spirit of the invention and its definition as set forth in the following claims.

I have shown, in Fig. 1, one end of the trough 1 connected with a concrete head wall structure 7 by means of a well known form of joint comprising a transverse bead 8 formed in the trough and fitted into a corresponding groove in the head wall. A compression rod 9 lies within the concavity of said bead, and is pressed down to clamp the trough against the head wall by clips or plates, one being shown at 10, bolted to the top of said head wall. I have also shown a horizontal bend or angular deflection in the flume, formed by a short trough section 11. The joints between the sections 1 and 11 are of well known form comprising interfitting transverse beads 12 clamped together by interior compression rods 13 and the exterior tension and suspension rods 4, the ends 105 of the compression rod bearing against the bottom of the cross member 6.

The angle section 11 is formed, to the same cross sectional curve as the sections 1, from a sheet of metal of the shape shown in Fig. 4, i. e. 110 shorter at one side than the other. The ends of the sections 1 connected with said angle section are commonly perpendicular to the longitudinal axes of said sections 1, so that the entire deflection occurs in the section 11. In order that the 115 meeting ends of the sections 1 and 11 will be in true vertical planes when the sheets are bent to the compound curve described above, it is necessary to cut the ends of the angle section 11 (its 120 longer edges being herein termed its ends) upon reverse curves, as shown in heavy solid lines at 14 in Fig. 4. This figure also illustrates clearly the effect of distortion of the trough in producing longitudinal stresses at its joints, thereby loosening 125 said joints and causing leakage. If the sheet 11 were to be formed to the curve of maximum deflection e of Fig. 3, its ends would have to be 130 cut upon curves represented by the broken lines e' in Fig. 4, and if it were to be formed to the curve of minimum deflection f of Fig. 3, its ends would have to be cut along the broken lines f' of Fig. 4, in order to make said ends lie in vertical 135 planes, i. e. to match evenly, with the ends of the sections 1. If the trough were to be semicircular, as at b in Fig. 3, the curve of the ends of the section 11 would depart still further from the curves e' of Fig. 4, as shown by the light solid line b'.

Now, obviously, if the sheet 11 were cut along the lines b', and bent to semicircular form, when maximum load distortion occurred, it would tend 140 to spread the angle joints, longitudinally of the trough, to an extent equal to the distance between the lines b' and e', and such longitudinal stress would, and in practice does, cause leakage at the joints, unless some form of expensive expansion joint is employed. However, by forming the trough initially to the compound curve 1a described above, and by cutting the ends of the angle sections along the lines 14 of Fig. 4, which have been determined to be the mean between maxi- 145

mum and minimum distortion, I reduce the longitudinal stress to that represented by the distance between the lines 14 and e' , or 14 and f' , which is sufficiently small to cause no trouble.

5 Distortion of the trough also causes longitudinal stress at the joint between the sheet metal section 1 and the concrete head wall 7, because as the bottom of the trough sags and its sides draw inwardly, under load, the upper portions of the 10 sides tend to pull longitudinally away from the rigid concrete head wall, which tends to pull the bead 8 out of its seating groove in the concrete. This difficulty is also eliminated, at least to sufficient extent, by making the sheet metal trough 15 to the above described compound curve, which reduces its maximum possible load distortion to a negligible amount. The concrete head wall 7 should, of course, be formed to the same curve.

I claim:—

1. A flume trough comprising a sheet of metal initially bent upon an arc of compound curvature, the length of said arc being equal to one half the circumference of a circle whose diameter is the width across the top of said trough, the radius of the side portions of said trough being greater than the radius of said circle, and the radius of the bottom portion being less than the radius of said circle.

2. A flume trough comprising a sheet of metal initially bent to compound cross sectional curvature, the radius of the side portions of the trough being greater than one half the width across its top, and the radius of the bottom portion being less than one half said width.
